ELECTROMAGNETIC RELAY

Bertil S. Bengtsson, New Britain, Conn., assignor to The Hart Manufacturing Company, Hartford, Conn., a corporation of Connecticut

Application March 10, 1958, Serial No. 720,333

11 Claims. (Cl. 200—104)

This invention relates to electromagnetic relays, and more particularly to improved and novel structure for biasing the contact carrier of such a relay in a manner to gain greater dependability and life with reduction in the cost of manufacture.

A primary object is to provide novel means for transversely biasing the contact carrier of a relay armature to effect a more uniform application of tension to the contact carrier than has heretofore been obtained with the leaf or coil springs commonly employed for that purpose.

A further object is to provide an improved contact carrier biasing spring which reduces, by damping out, undesirable carrier oscillations introduced by coil type biasing springs.

Other objects are to reduce the number of required parts in a relay assembly; to simplify fabrication of the housing-like supporting structure in a manner to utilize portions thereof as the sole fastening means for the parts housed thereby; to permit assembly of the device without the use of screws or rivets; to permit installation, removal and replacement of the tensioning spring or springs without complete disassembly of the cooperating components; and to insure greater dependability and longer spring life than has heretofore been obtained in relay switches of this general type.

Other objects will be in part obvious, and in part pointed out more in detail hereinafter.

The invention accordingly consists in the features of construction, combination of elements and arrangement of parts which will be exemplified in the construction hereafter set forth, the scope of the application of which will be indicated in the appended claims.

In the drawings:

Fig. 1 is a vertical section of an assembled solenoid operated multiple contact relay switch incorporating the invention.

Fig. 2 is a plan view of the base portion of the switch of Fig. 1 with the cover and solenoid removed to show the contact and contact carrier assembly.

Fig. 3 is a sectional view taken along lines 3—3 of Fig. 2.

Fig. 4 is a sectional view taken along line 4—4 of Fig. 2.

Fig. 5 is a view similar to that of Fig. 2, showing non-symmetrical biasing of the contact carrier to obtain sequential operation of the contacts with one set of contacts opening and then closing prior to corresponding action of the other set.

Fig. 6 is a section along line 6—6 of Fig. 5.

The drawings disclose the invention as embodied in a solenoid operated relay switch 10 comprising a chambered base 11 of insulating material in which a spring biased contact carrier is slidably mounted to actuate a pair of switch contact connecting bars, one at each end of the carrier, with each bar having circuit controlling end portions operatively disposed between paired contacts. A cover 12 is pressed fit to base 11 and provides

2

support for an actuating solenoid 13 mounted therein to depend from the top wall of cover 12. A top pole piece 14 is clamped between the top wall of cover 12 and an electromagnetic coil 17 of solenoid 13, with a lower pole piece 15 and insulating spacer 16 supported on the top of base 11. The pressed fit relation between cover 12 and base 11 maintains lower pole piece 15 and spacer 16 firmly clamped between the lower end of coil 17 and the top surfaces of base 11, proper alignment being insured by snug fit of those parts with cover 12.

Solenoid 13 is of known construction with the windings of coil 17 encircling a metallic center-bored core 18 having an upper integral tubular portion riveted marginally of an aperture in cover 12. An armature 20 of magnetic material is mounted on a brass shaft 22, bossed at 23 for slideable engagement in the bore of core 18, with a smaller boss 24 about which the lower end of a helical spring 25 fits, the upper end of spring 25 being adjustably positioned by screw 28. Armature 20 has a carrier 20 contacting plunger 26 mounted axially to depend therefrom, a shading coil 29 being provided in core 18 if required for A.C. operation. Carrier 31 is urged upwardly toward plunger 26 by one or more wire-like springs 45, 46, as more fully described below, the tension of spring 25 being sufficient, with solenoid 13 de-energized to overcome said upward carrier bias and force carrier 31 and a pair of connected contact bars 32 downward to a lower switch closing position. Energization of solenoid 13 results in armature 20 being retracted to the position shown in Figs. 1 and 2 to further compress spring 25, removing the downward bias on carrier 31 through armature 20 to allow the urge of the wire-like springs to return the carrier and contact bars to an upper switch closing position.

Base 11 may be a plastic die casting or the like, in the form of an upwardly open housing in which circuit-controlling mechanism associated with carrier 31 operates in response to energization or de-energization of solenoid 13. The various elements comprising that mechanism are securely fastened to base portions or supported thereby without use of screws or rivets, with spaced terminal strips 34a, 35a supporting paired contact points 34 and 35, preferably moulded integrally therewith to extend through the bottom base wall. Referring to Figs. 2 and 3, carrier 31 is slidably mounted in a vertical plane with a contact bar 32 connected to each end thereof for alternate circuit closing engagement with upper contacts 34 or lower contacts 35. Like paired contacts are associated with each bar 32, hence each bar controls opening or closing of two separate circuits in response to solenoid action. Bars 32 are positioned in slots 36 at each end of carrier 31 and laterally notched at 33 for locked engagement with carrier 31.

As best shown in Figs. 2 and 3, a pair of wire-like spring elements 45 and 46 are disposed within the central chamber defined by walls 39 and 40 to extend the length thereof in spaced relation transversely of carrier 31 which is provided with a pair of spaced bores 47 and 48 through which springs 45 and 46 project. The opposite ends of the springs are supported by shoulders 50 formed integrally with the base side wall and positioned above bores 47 and 48 with contactor bars in the top switching position shown in Fig. 3. Hence, the springs are arced downwardly under pressure to bias carrier 31 into the upward switch closing position, it being evident that as carrier 31 moves downwardly under the urge of spring 25 upon de-energization of solenoid 13 to position contact bars 32 in the lower switching position, the bias of springs 45 and 46 is increased. Upon energization of solenoid 13 and resultant retraction of armature 20 against spring 25 to remove the bias of spring 25 from carrier 31, contact bars 32 are rapidly returned

by the urge of springs 45 and 46 to the upper Fig. 1 position.

With solenoid 13 energized, plunger 26, as shown in Fig. 3, still projects through an aperture in spacer 16 in firm engagement with the upper surface of carrier 31 by reason of the upward urge of springs 45 and 46, thus insuring positive contact therebetween to prevent possible chattering. Upon de-energization of solenoid 13, spring 25 moves armature plunger 26 downwardly to depress carrier 31 and bars 32 from the heavy line position shown in Figs. 3 and 4 to the dotted line position shown therein to break contact points 34 and connect contact points 35. Since the downward urge of spring 25, with solenoid 13 de-energized, is substantially greater than the counter urge of transverse springs 45 and 46, positive contact is insured between bars 32 and lower spaced contacts 35. Upon energizing solenoid 13, springs 45 and 46 rapidly return armature 20 to the Fig. 1 position, but since solenoid armature 20 is drawn upwardly against the substantial bias of helical spring 25, the transverse carrier springs operate to aid in the smooth return of armature 20 without resulting chatter. The clearance between the cylindrical surface of armature 20 and the cylindrical inner wall of the chamber in which it axially moves is such that as the armature is rapidly returned to the Fig. 1 position, entrapped air is metered through the annular channel therebetween to effect a dash-pot action to supplement the compression of spring 25 to insure smooth armature deceleration.

Elongate springs 45 and 46 of piano wire or the like of a gage to introduce the desired bias, positioned symmetrically of carrier 31 as shown in Fig. 2, insure horizontal positioning of carrier 31 during depression by plunger 26 and return, hence both connector bars 32 make and break contact with paired contacts 34 and 35 at approximately the same instant. The relay structure may easily be modified by eliminating one of those two springs, such as spring 46, to provide time delay between the respective movements of connector bars 32 due to a resulting tilt of carrier 31 as force is applied by plunger 26. With a single spring, such as spring 45, but of heavier gage wire, or two springs of the same gage projecting through the same carrier aperture 47, as shown at 45a, Fig. 6, carrier 31 is non-symmetrically biased. With the carrier and connector bars in the upper switch closing position of Fig. 3, such non-symmetrical bias insures firm circuit closing contact between each bar 32 and paired contacts 34. However, upon the downstroke of the armature, plunger 26 depresses carrier 31 at a position eccentric to the position of applied spring bias in carrier bore 47, to tilt carrier 31 on the downstroke as shown in dotted lines, Fig. 6.

As a result, the long or right hand portion of carrier 31, as viewed in Fig. 5, causes bar 32 to break from its associated contact points 34 prior to a corresponding break between the corresponding bar 32 at the opposite end of the carrier and its contact points, thus introducing time delay between those breaks. For the same reason, contact between the right hand bar 32 and lower spaced contacts 35 is made prior to corresponding contact between the left hand bar 32 and its associated contacts 35, hence equal time delay between breaking and making contact by each bar and its associated contacts is inherent in the eccentrically biased modification of Fig. 5. For a like reason, the same magnitude of time delay is obtained on the upstroke, and while the tilt angle involved is the same, the left hand bar of Fig. 5, more heavily biased since closest to springs 45, and for that reason the trailing bar on the downstroke is the first to break contact on the upstroke, hence a reversal of the order of time delay occurs on the upstroke. A sequence of operation is thus obtained, which may be predetermined through proper selection of the gage and physical properties of wire-like springs 45 and 46.

The improved relay above described permits assem-

bly without the use of screws or rivets, since the terminal strips find their support in the bottom wall of base 11; bars 32 interlock with opposite ends of carrier 31 in a manner to be maintained in position by shouldered portions integral with base 11; carrier 31 reciprocates in a guideway defined by portions molded integrally in base 11; and springs 45 and 46 rest on shoulders also formed integrally with the base sidewalls. The construction thus utilizes a minimum number of parts which are easily assembled, substantially to reduce manufacturing cost. As is well known, relays of this general type by employing leaf or coil springs are prone to develop chatter under certain operating conditions, due to electromagnetically induced fundamental or harmonic vibration of the switching elements at certain resonant frequencies. The arrangement of elements in the relay above-described is such that the counter-biasing of the carrier spring or springs by the solenoid armature spring in co-operation with the dash-pot effect of the solenoid armature greatly reduces any tendency toward either fundamental or harmonic vibration thereof.

I claim:

1. In an electromagnetic relay, a contact-controlling carrier mounted for movement between upper and lower switching positions, an elongate wire-like spring disposed transversely of said carrier with a central portion in contact therewith, said spring being mounted under longitudinal distortion to urge said carrier toward an upper switching position, a solenoid positioned above said carrier and having an armature biased downwardly to depress said carrier against the bias of said transverse spring and into a lower switching position, said armature being retracted upon solenoid energization to remove the downward carrier bias with resulting movement of said carrier, under urge of said transverse spring, to the upper switching position.

2. The device of claim 1 wherein said carrier is biased by a pair of spaced elongate transverse springs disposed symmetrically of the center of said carrier.

3. In an electromagnetic relay, two groups of spaced apart stationary contacts having their contact surfaces in parallel planes, each group comprising two pairs of spaced contacts, a movable carrier disposed transversely of said two groups, a contact bar mounted at each end of said carrier for alternate contacting engagement with each of said two pairs of contacts, an elongate spring mounted to be arced transversely of said carrier with the center of said spring engaging said carrier, whereby said contact bars are spring biased to engage one set of said paired contacts and said carrier may be moved against the bias of said spring to cause said bars to engage the opposite set of contacts.

4. The device of claim 3 including a solenoid having an armature engaging said carrier, spring means biasing said armature against said carrier under sufficient urge to overcome the counter-bias of said transverse spring and move the carrier-mounted bars into engagement with the opposite paired contacts, said solenoid, when energized, overcoming the means biasing it against the carrier to allow said transverse spring to bias the bars against the opposite contacts.

5. The device of claim 3 including a pair of elongate springs symmetrically spaced transversely of said carrier.

6. In an electromagnetic relay, a base, stationary spaced pairs of upper and lower contacts supported on the base, movable contact bars extending between pairs of stationary contacts, a carrier connected to said bars, means forming a resilient support for the carrier and urging the contact bars toward contacting engagement with the upper stationary contacts, said means comprising a wire-like spring disposed transversely of said carrier with the ends thereof supported by said base and the center thereof engaging said carrier, said spring being longitudinally arced downwardly to bias the contact bars upwardly, spring means disposed above said carrier and

in contact therewith to urge the carrier downwardly against the bias of said transverse spring to maintain said bars in contacting engagement with the lower contacts, and electro-magnetic means for overcoming, when energized, said last mentioned spring means to allow said transverse spring to maintain said bars in contact with said upper contacts.

7. The device of claim 6 including a pair of wire-like springs disposed transversely of said carrier in engagement therewith at points symmetrically spaced in respect to the major axis thereof.

8. In an electromagnetic relay, two spaced groups of fixed switch contacts, each group comprising two pairs of spaced contacts in parallel spaced relation to corresponding pairs in the opposite group, an elongate carrier positioned transversely of said spaced groups, means mounting said carrier for movement in a plane normal to the plane of said spaced contacts, a pair of contactor bars fixed to opposite ends of said carrier in a position to be moved into contact engagement between said paired spaced contacts by movement of said carrier, a wire-like spring disposed transversely of the plane of said carrier with a central portion engaging the carrier and the ends thereof positioned to maintain said spring bowed downwardly and urge said contact bars into biased engagement with one set of spaced contacts.

9. In an electromagnetic relay, a slidably mounted carrier, plural pairs of spaced contacts, contact bars carried by said carrier for movement between said pairs of spaced contacts for bridging engagement therewith, spring means biasing said carrier toward engagement of said contact bars with one set of spaced contacts, said means comprising a pair of elongate wire-like springs projected through said carrier with ends of said springs anchored in a position to maintain said springs under longitudinal arc, a solenoid having a spring-biased armature in contact with said carrier to urge it in a direction to overcome the bias of said wire-like springs and maintain said contact bars engaged with the other set of spaced contacts, said solenoid, when energized, removing the downward bias on said armature to allow the wire-like springs to move the contact bars into engagement with said first mentioned contacts.

10. In a switch assembly, a housing of electrical insulating material including side and inner walls defining two lateral and one central chamber, a channel formed in said side and inner walls extending transversely of said

chambers at the midpoint thereof, a switch bar carrier slidably disposed within said channel, a wire-like spring mounted under longitudinal tension within said central chamber transversely of said channel with a central portion thereof in biased engagement with said carrier to urge it upwardly of said channel, a switch bar disposed in each of said lateral chambers and mounted to opposite ends of said carrier, upper and lower fixed sets of spaced switch contacts positioned in said lateral chambers on opposite sides of said switch bars and in the path of movement thereof, and a solenoid having a spring-biased armature positioned to depress said carrier and move said switch bars against said lower switch contacts, said bars being moved upwardly under urge of said transverse spring to engage said upper switch contacts upon relief of said carrier-depressing bias by energization of said solenoid.

11. In an electromagnetic relay, a housing-like base, plural pairs of upper and lower contacts fixed to said base, a pair of movable contact bars, each positioned to extend between pairs of fixed contacts, a carrier slidably mounted in said base for movement vertically thereof with the ends of said carrier connected to said bars, and means biasing said carrier in a position for engagement of said bars in contact with the upper fixed contacts of said pairs, said means comprising a pair of elongate springs disposed transversely of said carrier and symmetrically spaced in respect to the center thereof, means connecting the ends of said springs to said base at positions maintaining said springs longitudinally arced in either position of contact between said bars and said fixed contacts, a helical spring for the biased depression of said carrier against the bias of said transverse springs from a position of bar contact with upper fixed contacts to a position of bar contact with lower fixed contacts, and a solenoid associated with said helical spring to eliminate, when energized, the bias thereof with resultant return of said contact bars to engage said upper fixed contacts.
